[57] CLAIM

The ornamental design for a combined clamping gland and ring for an electrical conduit, substantially as shown and described.

DESCRIPTION

FIG. 1 is a perspective elevational view of a combined clamping gland and ring for an electrical conduit showing our new design;

FIG. 2 is a cross sectional view along lines 2—2 of FIG. 1 thereof;

FIG. 3 is a perspective elevational view of another embodiment of a combined clamping gland and ring for an electrical conduit showing my new design;

FIG. 4 is a cross sectional view along lines 4—4 of FIG. 3 thereof.

Fig. 1.Fig. 2.Fig. 3.Fig. 4.
